CLAIM

The ornamental design for a command device, as shown and described.

DESCRIPTION

FIG. 1 is a first perspective view of a command device showing our new design.

FIG. 6 is a left side elevational view of the command device. FIG. 7 is a top plan view of the command device; and, FIG. 8 is a bottom plan view of the command device.

In the drawings, the broken lines depict a portion of the command device and form no part of the claim.

The command device is intended to be used as a device for generating commands for a security system.
